UNITED STATES PATENT OFFICE.

NEIL T. ALBRIGHT AND BURTT J. HUBBARD, OF KOKOMO, INDIANA, ASSIGNORS TO
KOKOMO AUTOMOTIVE MFG. CO., OF KOKOMO, INDIANA, A CORPORATION.

DESIGN FOR A WINDSHIELD WING.

Application filed January 30, 1923. Serial No. 5,029. Term of patent 7 years.

To all whom it may concern:

Be it known that we, NEIL T. ALBRIGHT, and BURTT J. HUBBARD, citizens of the United States, residents of the city of Kokomo, county of Howard, and State of Indiana, have invented a new, original, and ornamental Design for Windshield Wing, of which the following is a specification, reference being had to the accompanying drawings, forming a part thereof.

Fig. 1 is a front elevation of the windshield wing. Fig. 2 is a top plan view.

We claim.

The ornamental design for a Windshield wing, as shown.

NEIL T. ALBRIGHT.
BURTT J. HUBBARD.
